(57) **CLAIM**

The ornamental design for a base for a detachable camera device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, left side perspective view of a first embodiment of a base for a detachable camera device showing our new design;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof;

FIG. 8 is a top, front, left side perspective view of a second embodiment of a base for a detachable camera device showing our new design;

FIG. 9 is a front view thereof;

FIG. 10 is a back view thereof;

FIG. 11 is a left side view thereof;

FIG. 12 is a right side view thereof;

FIG. 13 is a bottom view thereof; and,

FIG. 14 is a top view thereof.

The portions of the design shown in broken lines are for the purpose of illustrating environment only and form no part of the claimed design.
